UNITED STATES PATENT OFFICE.

FRANCIS I. DU PONT, OF WILMINGTON, DELAWARE, ASSIGNOR TO DELAWARE CHEMICAL ENGINEERING COMPANY, OF WILMINGTON, DELAWARE, A CORPORATION OF DELAWARE.

LIQUID-VENDING DEVICE.

Application filed August 5, 1922. Serial No. 579,792.

This invention relates to an improvement in liquid vending devices, and more particularly relates to devices for vending gasoline in which the price varies from time to time.

The object of my invention is to provide a simple and efficient device of this character which will enable a purchaser to obtain a predetermined quantity of liquid for each coin inserted, and which is so arranged that the purchaser can observe the amount of liquid to be delivered for the coin inserted.

A further object of my invention is to provide means for preventing the operation of the device if the parts are tampered with to obtain gasoline without inserting a coin.

The specific device illustrated comprises a measuring device which is so arranged that the purchaser can observe the quantity of gasoline contained therein before he inserts the purchase coin, together with mechanism for delivering the gasoline to the measuring device from a reservoir at a lower level. The delivery mechanism is arranged to deliver a greater quantity of gasoline to the measuring device than the maximum capacity of said device, the surplus flowing back to the reservoir. The said mechanism is also arranged to be actuated by the purchaser before the insertion of the coin, and is also so arranged that no gasoline will be raised from the reservoir if the observation windows or any portion of the enclosing casing is open. The device is also provided with coin-controlled mechanism which is arranged to prevent the discharge of gasoline from the measuring device until the proper coin has been inserted and the mechanism has been released by the coin.

The precise nature of my invention will be best understood by reference to the accompanying drawings, which will now be described, it being premised, however, that changes may be made in the details of construction without departing from the spirit and scope of my invention as defined in the appended claims.

Fig. 1 is a sectional view of one form of device made in accordance with my invention.

Fig. 2 is a detail sectional view of the coin-controlled mechanism.

Fig. 3 is a perspective view of the coin slide.

Fig. 4 is a side elevation of the coin-controlled releasing device.

In these drawings, the reference character *a* designates an oil reservoir or tank, such as is usually located underground, and which is provided with the usual filling pipe, *b*, not shown.

Mounted above the reservoir in any desired position for dispensing gasoline is an air-tight casing *b*. *c* is a measuring device within the casing *b*, which is supported on trunnions *d* which are rotatably mounted in bearings on the casing. One of these trunnions extends through the casing and is provided with an operating crank *e*. The bearing through which this trunnion extends is provided with a stuffing box or any other suitable means for forming an air-tight joint for the purpose hereinafter described.

Mounted within the casing is an air pump having a cylinder *g* and a liquid pump having a cylinder *h*. These pumps are also provided with pistons which are connected to each other by means of a rod *i*, which is provided with a rack engaged by a toothed sector *j*. The sector is connected to a shaft *k* journaled in bearings on the casing and is also provided with an operating lever *k* on one end thereof. The end of this shaft to which the lever *k* is connected also extends through the casing and is so mounted as to form an air-tight joint. *l* is a pipe extending from the reservoir *a* to the cylinder *h* and *f* is a second pipe extending from said cylinder to the measuring device *c*. Both of these pipes are provided with check valves which are so arranged that when the piston in cylinder *h* is raised liquid will be drawn from the reservoir to the cylinder and when the piston is depressed, liquid will be forced from the cylinder to the measuring device *c*.

provided, however, the parts are in their normal operating positions. Extending from pipe *l* is a pipe *n* having an outlet controlled by a valve *o*. The valve *o* is carried by a rod connected to a bellows *p*, which is supported at one end from an adjustable spring *q* supported from the casing, while its other end is supported on the end of a pipe *19* in communication with its interior and

with atmosphere and by which the interior of the bellows is maintained under atmospheric pressure, while the exterior thereof is acted on by the pressure within the casing *b*, the parts being so arranged that when the pressure within the casing falls to atmosphere the valve *o* will be raised from its seat, as illustrated.

Extending from the cylinder *g* to the atmosphere is a pipe *r*, having check valves arranged to admit air to the cylinder *g* when its piston is lowered and to force air into casing *b* when said piston is raised.

s is a receiver in the casing *b* having an outlet pipe to the exterior of the casing through which the liquid or gasoline is delivered. This pipe may be provided with a suitable flexible pipe or hose for delivering gasoline to supply tanks of automobiles.

20 The outlet from the receiver is controlled by a valve *t*, which is seated by gravity and is raised from its seat by the lever *u* when the lever is tipped by the measuring device, as shown in dotted lines in Fig. 1.

25 In Figs. 2 to 4, I have shown one form of coin-controlled mechanism for locking the measuring device *c* in its upright position. This mechanism is located within the casing *b* and comprises a cam member *v* connected 30 to the trunnion *d* on the end opposite the trunnion to which the crank *e* is connected. The cam is provided with a slot 16 which is arranged to be engaged by a locking pin *w* when in its elevated position, and is also pro-

35 vided with a high portion for actuating the coin clearing mechanism. The locking pin *w* is provided with a stirrup in its central portion, as shown in Fig. 4, which straddles a coin slide *x*, and is provided with a table 40 for the reception of a coin from a coin slot in slide *x*. The lower end of the locking pin *w* is connected to a counterbalance *y* by means of link and lever connections, as clearly shown in Fig. 2, the arrangement 45 being such that when no coin is on the table of the pin *w* said pin is raised by the weight *y* and when the parts are in the positions shown in the drawings the slot in cam *v* is in line with pin *w*.

50 Mounted to slide in guides below slide *x* is a slide *z*, having a rack thereon which is arranged to be actuated by a sector 6. This sector 6 is actuated by a bell crank 7 connected thereto by a link 8. The bell crank 7 is arranged to 55 be moved in one direction by the high portion of cam *v* and in the other direction by a spring 9.

The side of the measuring device as well as the side of casing *b* are provided with 60 glass portions so that the purchaser may see the amount of fluid in the measuring device, as hereinafter described.

The side of the measuring device may be graduated in any desired manner to indicate 65 quantity or price of the fluid, which will be

denoted by the level of the fluid in the measuring device.

The measuring device *c* is provided with overflow openings at various heights, which are closed by any suitable plugs 10, in the form shown there being three such openings, the lower two of which are plugged, while the upper opening is open so that the level of the liquid, which can be retained therein, will be on a level with the lower edge of the upper opening.

The receiver *s* may also be provided with glass sides and graduations if desired so that the purchaser can see the amount of fluid delivered to the receiver from the measuring device.

The device is operated in the following manner: The crank or lever *k* is depressed, which will raise the pistons of both pumps. In the preliminary upward movement of the pistons, the upper end of the piston rod *i* will enter and pass through an opening 17 in the trunnion *d* and lock the measuring device *c* in its elevated position. During this upward movement, the air drawn into the cylinder *g* through pipe *r*, on the downward movement of the piston will be forced into the casing *b*, increase the pressure therein, and close valve *o* through the medium of bellows *p*.

This closing of the valve *o* will permit gasoline to be sucked from reservoir *a* to cylinder *h* and the pumps are now operated to fill the measuring device *c*.

When the gasoline overflows from the measuring device, lever *k* is raised to the position shown to release the measuring device. A coin 18 is now placed in the coin slot in slide *x*, which is then pushed into the case until the stop 11 on the end of the slide and stop 12 extending from the casing engage each other. This shifting of the slide will bring the coin slot and coin over table 14 on pin *w* and the coin will be deposited on the table. The weight of the coin will depress pin *w* and withdraw the upper end from the slot in cam *v* and thereby unlock the measuring device *c*.

Lever *e* is now raised and the contents of measuring device *c* are dumped into receiver *s*, in which they are retained until valve *t* is opened.

If the purchaser desires to check up the quantity of fluid delivered to receiver *s*, he can do so by allowing the fluid to flow from the measuring device to the receiver without resting the weight of the measuring device on lever *u*. When it is desired to empty receiver *s*, the measuring device is allowed to rest on lever *u*, which will raise valve *t* and permit the liquid to flow out through the outlet, past valve *t*.

After all of the liquid flows from the receivers *s*, the air pressure in casing *b* will be relieved through valve *t*, and as the pressure is the same on both sides of bellows *p*, valve *o* will be opened.

120
125
130

During the dumping of the measuring device, slide *z* will be actuated and move the coin from the table 14 of pin *w* and deliver it to chute 13, through which it will pass to 5 a coin box in casing *b*.

When the measuring device is in its dumping position or in any position other than an upright position, the pumps will be locked as the piston rod *i* cannot be actuated 10 as the upper end thereof is locked against upward movement by the trunnion *d*.

When it is desired to refill the measuring device, it is necessary to move the measuring device to its vertical position, to align 15 the opening in trunnion *d* with piston rod *i*. This shifting of the measuring device will permit valve *t* to close, permit spring 9 to return slide *z* to the position shown, and as soon as the slot in cam *v* is in line 20 with rod *w*, the rod will be shifted to locking position by the weight *y* and lock the measuring device in its vertical position and align the opening in trunnion *d* with piston rod *i*.

As the pumps cannot be operated when the measuring device is in dumping position with valve *t* open, there is no danger of 25 fluid being stolen when valve *t* is open by operating the pump and collecting fluid, which would splash or drain into the receiver.

The overflow from measuring device *c* passes to casing *b*, which is returned to reservoir *a* through pipe *m*, having a check 35 valve 15 therein. The pressure of the spring of check valve 15 is sufficient to overcome the light air pressure required in casing *b* for actuating bellows *p*, but the pressure of this spring is not sufficient to overcome the weight of a column of fluid in pipe *m* extending from reservoir *a* to casing *b*.

If desired, a suitable check valve leading to the atmosphere may be placed in the wall of casing *b* to prevent the building up of air pressure therein beyond a predetermined 40 maximum.

The valve *o* provides means for preventing the operation of the fluid pump if any of the glasses covering the windows are broken, as the pump would not raise the 45 fluid, but would only suck air if the valve *o* were open.

The advantages of my invention result from the provision of a vending device in which the purchaser can measure and note 55 the amount of fluid to be delivered before depositing the purchasing coin, and which is so arranged that on further fluid can be drawn from the reservoir or supply after the measuring device is shifted from its receiving position.

A still further advantage results from the provision of means for preventing the drawing of fluid from the main reservoir and delivering it to the delivery outlet if the

pressure in the casing is not above atmospheric pressure.

I have not disclosed any spurious coin detector, but I desire it to be understood that any type of detector can be used in connection therewith.

Having now fully described my invention, what I claim and desire to protect by Letters Patent is:

1. A fluid vending machine having means for elevating fluid from a supply reservoir 75 to a measuring device, means controlled by the elevating device for preventing discharge from the measuring device when the elevating device is delivering, means for discharging the fluid from the measuring device, a locking device for the discharging mechanism, and coin-controlled means for the locking device.

2. A fluid vending device comprising a fluid measuring device, means operable to supply fluid to the measuring device, means for shifting the measuring device to a discharging position, means associated with the means for supplying fluid and the measuring device adapted to cooperate to prevent operation of the means for supplying fluid when the measuring device is shifted to a discharging position and to prevent shifting of the measuring device when the means for supplying fluid is delivering.

3. A fluid vending machine comprising a measuring device, means operable to supply fluid to the measuring device, means operable for discharging fluid from the measuring device, means operable by the measuring device for the delivery of fluid discharged in said measuring device, and means adapted to prevent operation of said fluid supply means when said means for discharging fluid from said measuring device is operated.

4. A fluid vending machine having a measuring device, a pump for raising fluid from a supply to the measuring device, means operable to discharge the contents of the measuring device and deliver it to a suitable delivery means, means for preventing the operation of the pump when the means for discharging the contents of the measuring device is operated, and a coin-controlled lock for preventing operation of the means for discharging the contents of the measuring device.

5. A fluid vending device having a pivoted measuring device, means for varying the quantity of fluid to be retained thereby, a fluid supply at a lower level than the measuring device, a fluid pump for raising fluid from the supply to the measuring device, a receiver for receiving the fluid from the measuring device, means to shift the measuring device from a filling position to a discharging position or from a discharging position to a filling position, and means

associated with the pump and the measuring device adapted to cooperate to prevent shifting of the measuring device to a discharging position when the pump is actuated and to prevent actuation of the pump when the measuring device is shifted to a discharging position.

6. A fluid vending device having a casing, a fluid reservoir, a fluid delivery pipe extending from the reservoir to the casing, a fluid outlet pipe leading from the casing means for increasing the pressure in the casing above atmospheric pressure, means in the casing for delivering fluid from the reservoir to the outlet pipe through the delivery pipe, pressure-controlled means for preventing the delivery means from acting when the pressure in the casing is below a predetermined point, and a coin-controlled lock for a portion of the fluid delivery means.

7. A fluid vending device having a fluid reservoir, a fluid measuring device, a casing surrounding the measuring device, an air pump for raising the pressure in the casing above atmospheric pressure, a pump for raising fluid from the reservoir to the measuring device, means controlled by the pressure in the casing for rendering the fluid pump active or inactive, means for discharging the measuring device to an outlet,

and a coin-controlled lock for the means for delivering the fluid to the outlet.

8. A fluid vending device having a fluid reservoir, a fluid measuring device, a casing surrounding the reservoir, means for raising the pressure in the casing, a pump for raising fluid from the reservoir to the measuring device, means controlled by the pressure in the casing rendering the pump effective or ineffective, and means for discharging the measuring device to an outlet.

9. A fluid vending device having a fluid reservoir, a fluid measuring device, a casing surrounding the reservoir, an air pump for raising the pressure in the casing above atmospheric pressure, a pump for raising fluid from the reservoir to the measuring device, means controlled by the pressure in the casing for rendering the fluid pump effective or ineffective, means for discharging the measuring device to an outlet, a coin-controlled lock for the means for delivering the fluid to the outlet, and means associated with the fluid pump and the measuring device arranged to cooperate to prevent delivery from the measuring device to the outlet while the pump is delivering.

In testimony of which invention, I have hereunto set my hand, at Wilmington Delaware, on this 2nd day of August, 1922.

FRANCIS I. DU PONT.
